UNITED STATES PATENT OFFICE.

PAUL A. STOVER, OF RACINE, WISCONSIN, ASSIGNOR TO THE STOVER SIGNAL ENGINEERING CO., OF RACINE, WISCONSIN, A CORPORATION OF DELAWARE.

DESIGN FOR A DOOR FOR A VEHICLE SIGNAL LAMP.

Application filed August 17, 1925. Serial No. 14,501. Term of patent 3½ years.

To all whom it may concern:

Be it known that I, PAUL A. STOVER, a citizen of the United States, residing at Racine, Wisconsin, have invented a new, original, and ornamental Design for Door for a Vehicle Signal Lamp, of which the following is a specification, reference being made to the drawing forming a part thereof.

In the accompanying drawings, Fig. 1 is a front elevation of my door for a vehicle signal lamp.

Fig. 2 is a side elevation of the same.

I claim:

The ornamental design for a door for a vehicle signal lamp substantially as shown.

PAUL A. STOVER.
